DESIGN FOR A COOKING STOVE

Bertrand B. Kahn, Cincinnati, Ohio, assignor to The Estate Stove Company, Hamilton, Ohio, a corporation of Ohio

Application June 19, 1939, Serial No. 85,551

Term of patent 3½ years

To all whom it may concern:

Be it known that I, Bertrand B. Kahn, a citizen of the United States of America, residing at Cincinnati, in the county of Hamilton, State of Ohio, have invented a new, original, and ornamental Design for Cooking Stoves, of which the following is a specification, reference being had to the accompanying drawing, forming a part thereof.

The figure is a perspective view of a cooking stove showing my new design, the left-hand side of the stove being substantially like the side shown.

The design is characterized by the specific top covers and back guard panel in combination with the particular stove shown.

I claim:

The ornamental design for a cooking stove, substantially as shown and described.

BERTRAND B. KAHN.
